GARMENT HANGER BAR

Walton B. Crane, 4346 Matilija Ave.,
Sherman Oaks, Calif. 95681

Filed June 26, 1967, Ser. No. 7,593

Term of patent 14 years

(Cl. D33—8)

FIGURE 1 is a perspective view of a garment hanger bar showing my new design, with the portions of the center thereof broken away to indicate indeterminate length;

I claim:

The ornamental design for a garment hanger bar, as shown and described.
